UNITED STATES PATENT OFFICE.

CHARLES E. FARRINGTON, OF PHILADELPHIA, PENNSYLVANIA.

AGITATOR HANDLE.

Application filed February 28, 1920. Serial No. 362,097.

To all whom it may concern:

Be it known that I, CHARLES E. FARRINGTON, a citizen of the United States, residing at Philadelphia, in the county of Philadelphia and State of Pennsylvania, have invented new and useful Improvements in Agitator Handles, of which the following is a specification.

This invention has for its object to provide a handle for various uses but more particularly for the employment with barrel agitators, such for instance as illustrated in my application for Letters Patent, Serial No. 251,786, filed August 28, 1918.

15 The invention comprises an arm which may serve as a lever for rotating a member, such as a shaft or agitator, and a pin extending laterally from the end of the arm, which will serve as the crank to be grasped by

20 the hand. The pin is detachable from the arm, and, when not in use, is clamped in a groove or slot formed in the arm, by securing the arm by suitable fastenings against any substantially flat surface, e. g.,
25 the head of a barrel. Thus the pin may

23 the head of a barrel. Thus the pin may be dismounted and secured in its clamped position when the handle as a whole is not in use or is to be shipped. The arm, when used for effecting the rotation of an aci-

30 tator, may be formed with an enlargement to serve as the cover or closure of a hole in the head of the barrel, and may be provided with means to project into the hole for detachably engaging the end of the
35 agitator which is located within the barrel.

On the drawings.—

Figure 1 represents in section the upper end of a barrel containing an agitator, and provided with a handle embodying my invention.

Figure 2 represents a plan view of the arm with the crank-pin clamped in inactive position.

Figure 3 represents, on a larger scale, the 45 arm with the crank-pin in inactive position.

Figure 4 represents a cross-section on the line 4-4 of Figure 3.

Figure 5 represents a section on the line 5-5 of Figure 3.

50 Figure 6 represents a longitudinal section

through the arm with the crank-pin located in its active or operative position.

Referring to the drawings,—I have illustrated in Figure 1 the upper portion of a wooden barrel 10 having a head 11. Within the barrel is located a twisted blade agitator 12 which may be substantially similar to that illustrated and described in my application for patent hereinbefore referred to

The operating handle, which embodies the present invention, comprises an arm indicated as a whole at 13, having at one end a substantially circular head 14 which serves as a cover or closure for the aperture 15 in the center of the barrel head 11. The arm 13 is formed with an angular portion 16 connecting the head or cap 14 with the body of the arm, so that the latter lies in a plane spaced or separated from the plane of the barrel head. The outer extremity of the arm has a dependent boss 17 which terminates short of the barrel head, and which has a threaded aperture 18. As shown in Figure 3, the circular head has in its under face circular groove 19 to receive a packing ring 20 of rubber or other suitable material, and it also has ears 21 which are apertured at 22, as shown in Figure 2. An aperture 23 is formed in the head at a point equi-distant from the apertures 22, and through these three apertures 22, 22, 23, screws may be driven into the barrel head to secure the head 14 in place and thereby seal the opening in the barrel.

Inasmuch as the arm and its head may be utilized to effect the rotation of the agitator, the head or cap is formed with depending clutch members which project into the aperture 15 and form a journal engaging the wall of said aperture which serves as a bearing therefor. Said members likewise are constructed to engage the upper end of the agitator blade. As shown, the clutch members may be three in number as indicated at 24, 24, 25. The member 25 and one of the members 24 lie on one side of the agitator blade, and the other member 24 lies on the other side, so that, when the arm is rotated in a clockwise direction, it will rotate the blade; but, when the arm is rotated in the 10

reverse direction, the rotation of the blade is not properly effected. The reason for this is that ordinarily the blade, to accomplish its functions most effectively, should 5 be rotated in a clockwise direction only. Of course, the member 25 could be duplicated on the opposite side of the blade, so that the blade could be rotated as readily in one direction as in the other. The outer 10 walls of the lugs or members 24, 25, have a cylindrical curvature about a common center, so as properly to engage the cylindrical wall of the aperture 15.

The arm is provided with a crank pin by 15 which it may be rotated, but which, when not in use, may be nested in a recess in the arm. This pin may take any suitable or desirable form. As shown, it consists of an elongated stud 26 and provided at its opposite 20 site end with a screw thread 28 to enter into threaded engagement with the aperture 18 in the end of the arm 13, and a sleeve 29 which encloses the stud. The construction thus described permits the sleeve to be 25 moved to an extended position and to have a freedom of movement when it is grasped by the hand, in the act of revolving the stud about the axis of the agitator.

If the crank pin were permanently fixed 30 to the arm, it is evident that, in transporting the barrel, it would be easily broken or injured and would prevent the close packing of the barrels, and hence the crank-pin is detachable. I provide for assembling the pin 35 with the arm in such manner that it cannot be lost in transit. For this purpose, the arm 13 is formed on its under side with a recess in which the pin may be nested and clamped against the top of the barrel. This 40 recess may take the form of a slot 31 having beveled or concave side walls 32 for engaging the crank-pin. The slot is longer than the stud or sleeve, so that the crank-pin may be nested in the recess between the arm and 45 head of the barrel, and thus be clamped between the last-mentioned parts.

In practice, the agitator may be located 50 within the barrel, and the head or cap of the arm (with the packing 20 in place) located over the opening 15 in the head of the barrel, with the clutch members 24, 25, engaging the end of the agitator. The crank-pin, which is then detached or dismounted, is placed in the recess in the arm, and wood 55 screws or other fastenings are passed through the holes 22, 23, so as securely to fasten the head in place and to tightly close the opening 15. The crank-pin is thus securely clamped against dislocation in the recess, 60 and between the arm and the barrel. If desired, a fourth wood screw may be driven through the aperture 18 in the end of the arm into the head of the barrel, but this ordinarily is unnecessary. When the barrel 65 arrives at its destination, the wood screws

are removed, the crank-pin is secured to the end of the arm by screwing the stud 26 into the threaded aperture 18, and the arm may now be moved about its axis to operate the agitator.

Of course, other suitable means may be employed for securing the handle in place. In fact, the cap may be threaded to screw into a threaded opening in the head of the barrel or container, as shown in my said co- 70 pending application.

It will be noted, from an examination of Figure 1, that, when the crank pin is nested in the recess in the arm and thereby clamped in place, all portions of the arm are located below the plane at the edge of the chine of the barrel, so that there is little likelihood of the arm being broken or otherwise injured.

What I claim is:—

1. A handle for actuating a rotatable element, comprising an arm having a threaded aperture at one end and a crank-pin having a threaded end for engagement with said aperture so that said pin may be detachably 90 secured to said arm, said arm having in one face an open recess in which said pin may be nested and clamped against a flat surface when unscrewed from said aperture.

2. A handle for actuating a rotatable element, comprising an arm and a crank-pin adapted to be detachably secured to said arm, said arm having in one face an open elongated recess in which said pin may be nested and clamped against an adjacent 100 member, said arm having provisions by which it may be detachably secured to such member.

3. An handle for actuating an agitator, comprising an arm formed at one end to engage such agitator, and a crank-pin adapted to be detachably secured to said arm, said arm having in its under side a recess to receive said crank-pin, and adapted to be secured on a flat member with the pin clamped 110 between said arm and said member.

4. A handle for actuating an agitator, comprising an arm formed at one end with a head or cap to form a closure for an opening in the head of the barrel, and also adapted to be secured to said barrel head, and a crank-pin detachably secured to said arm, said arm having a recess to receive said pin and clamp it against said barrel head.

5. A handle for actuating an agitator, comprising an arm formed at one end with a head or cap to form a closure for an opening in the head of the barrel, and also adapted to be secured to said barrel head, said head having clutch members to project into 125 said opening for engagement with an agitator located in said barrel, and formed to constitute a journal for engaging the wall of said opening.

6. A handle for actuating an agitator, 130

comprising an arm formed at one end with a head or cap to form a closure for an opening in the head of the barrel, said head extending into said opening so as to constitute a journal rotatable in said opening and provided with clutch members for engaging an agitator located in said barrel, a crank-pin secured to the free end of the arm, and means by which said head may be secured in place. ¹⁰
In testimony whereof I have affixed my signature.

CHARLES E. FARRINGTON.
